INVENTOR.
J.M. DEAN

BY
Milton S. Grindall,
ATTORNEY

UNITED STATES PATENT OFFICE.

JOSEPH M. DEAN, OF SIOUX CITY, IOWA.

TOY CART.

Application filed April 17, 1922. Serial No. 554,236.

To all whom it may concern:

Be it known that I, JOSEPH M. DEAN, a citizen of the United States, and a resident of Sioux City, in the county of Woodbury and State of Iowa, have invented certain new and useful Improvements in Toy Carts, of which the following is a specification.

My invention aims to provide an improved child's toy cart, so constructed as to represent and travel with a waddling motion like a duck.

A further object of the invention is the production of a dirigible cart of the above sort.

Furthermore, the invention has for an object the production of a child's toy cart, simple and inexpensive in construction, yet sturdy and efficient in use.

With these and other objects in view, the invention, consisting in the construction, combination and novel arrangement of parts, will be fully understood from the following description, reference being had to the accompanying drawings, which form a part of this application and in which like characters of reference indicate corresponding parts throughout the several views, of which,—

Fig. 1 is a plan of a cart constructed in accordance with my invention.

Fig. 2 is a side elevation thereof, a portion being cut away to reveal characteristics otherwise concealed.

Fig. 3 is a rear elevation of the same, and

Fig. 4 is an inverted plan of a portion of the body.

Referring, now, to the illustrations the body of the device is flat and disposed in substantially a vertical plane, and designed to represent a duck in side elevation, the representation of the head, 5, and breast, 6, of the duck forming the front portion of the body, which is separate from the intermediate and rear portion of the body, indicated at 7. The front portion, 6, is mounted by travel wheels, 8, disposed on opposite sides of the said front portion and rotatably mounted on stud axles, 9, projecting laterally from the opposite sides of the said body portion. The body parts, 6 and 7, are suitably so pivoted together as to permit of relatively lateral movement between the said parts.

In the embodiment chosen for illustration I accomplish this by means of a rigid strap, 10, suitably secured to the upper edge of the

part, 6, and having a rearwardly overhanging portion, 11, and on the under side of the part, 6, is secured a rigid strap, 12, projecting rearwardly. Through the said straps, 10 and 12, and an opening, 13, in the body portion, 7, is extended a bolt, 14, which holds the parts, 6 and 7, against sagging yet permits free lateral movement of the front wheeled portion, 6, whereby the cart is readily steered. To prevent turning the said portion of the body too sharply, which would result in overturning of the cart, I provide means for limiting the lateral movement of the front portion, preferably consisting of a stop engageable with the rear end portion of the strap, 12, as by securing to the under side of the body portion, 7, a flat stop, 15, positioned in slightly spaced relation to the strap, 12, and so related thereto that the squared rear end of the strap, 12, will engage the stop, 15, to prevent lateral movement of the part, 6, in either direction beyond a determinate point, as will be clearly understood from Fig. 4. The upper edge of the body, 7, is straight and has mounted thereon a suitable seat, 16, the rear end portion of which rests upon and is suitably secured to laterally disposed boards, 17, or their equivalent positioned on opposite sides of the body, 7, and serving as supporting means for the rear bolster, preferably comprising a metal strip, 18, secured to the under side of the boards, 17, and having their end portions bent downwardly, as 19, to serve as bearings for the rear axle, 20, having fixed on its end portions travel wheels, 21. The said travel wheels, 21, are mounted eccentrically and in opposite phases whereby it is evident the cart in traveling is given a waddling motion in imitation of a duck. Extending transversely through the head, 5, is a fixed handle bar, 22, whereby the device is steered.

Having thus described my invention what I claim as new and desire to secure by Letters Patent of the United States, is,—

1. A toy cart embodying a flat body having approximately the side contour of a duck, the front and rear body portions being divided vertically, metal ears secured to the upper and lower edges of the front portion and overlapping the rear portion, a bolt projecting through the latter portion and said ears, whereby the front portion may swing laterally, wheels supporting the front portion, a rotatable axle on the rear portion,

- and travel wheels fixed eccentrically and in relatively different phases on the axle, to give the body a waddling motion when traveling.
- 5 2. A toy cart embodying a flat body having approximately the side contour of a duck, the front and rear body portions being divided vertically, metal ears secured to the upper and lower edges of the front portion 10 and overlapping the rear portion, a bolt projecting through the latter portion and said ears, whereby the front portion may swing laterally, a stop on the under edge of the rear body portion engageable with the lower of said ears to limit the lateral swing- 15 ing of the front body portion, wheels supporting the front portion, a rotatable axle on the rear portion, and travel wheels fixed eccentrically and in relatively different phases on the axle, to give the body a wad- 20 dling motion when traveling.
- In testimony whereof, I have hereunto set my hand this 15th day of April, 1922.
- JOSEPH M. DEAN.
